UNITED STATES PATENT OFFICE.

JAMES C. SNYDER, OF WABASH, INDIANA.

BURIAL-VAULT.

1,055,825.

Specification of Letters Patent. Patented Mar. 11, 1913.

Application filed July 13, 1912. Serial No. 709,201.

To all whom it may concern:

Be it known that I, JAMES C. SNYDER, citizen of the United States, residing at Wabash, in the county of Wabash and State 5 of Indiana, have invented new and useful Improvements in Burial-Vaults, of which the following is a specification.

My present invention pertains to burial vaults, and is designed more particularly as 10 an improvement on the burial vault constituting the subject matter of my Letters-Patent Number 950,681 of March 1, 1910.

One of the objects of the present invention is to provide a burial vault comprising a 15 base section and casket rests so constructed and relatively arranged that caskets can be arranged at various heights above the base section as occasion demands.

Another object of the invention is to so 20 construct the upper section that it can be readily lowered into a grave and effectually sealed to the base section.

Another object is the combination of the 25 features stated in a casket constructed with a view to preventing moisture gaining access to its interior.

With the foregoing in mind the invention will be fully understood from the following 30 description and claims when the same are read in connection with the drawings accompanying and forming part of this specification, in which:

Figure 1 is a perspective of the vault constituting the best practical embodiment of 35 my invention that I have as yet devised. Fig. 2 is a longitudinal vertical section of the same. Fig. 3 is a cross-section. Fig. 4 is a perspective of one of the casket rests.

Similar numerals of reference designate 40 corresponding parts in all of the views of the drawings.

The upper section 1 and the lower or base section 2 of my improved vault are respectively made of suitable plastic substance reinforced by reticulated metal 3 embedded 45 therein. This is the preferred embodiment of my invention, but I would have it understood that without involving departure from the scope of the invention as claimed, the 50 said sections may be made of any material compatible with their purpose, and may be reinforced or not in the discretion of the manufacturer. On its corners, and at its outer side adjacent its top the upper section 55 1 is provided with lugs the lower edges of which project outward beyond the major

portion of the section, and are under-cut and convex as shown. The said lugs, which are numbered 4, serve to enable rope loops to securely hold the section incidental to the 60 lowering of the section into a grave; it being understood that the bights of the loops are opposed to the ends of the section and disposed under the lugs 4, while at a point above the transverse center of the section the 65 loops are connected to a suitable lowering apparatus. The lower edges of the upright walls of the section 1 are increased in thickness, as indicated by 5, and are rounded as indicated by 6, so as to conform to the shape 70 in cross-section of the grooves in the base section and permit of the upper section being expeditiously and effectually sealed to the lower section by cement or other suitable material, so as to exclude air from the interior of the vault and confine a certain amount of air in the vault for a purpose 75 hereinafter set forth.

The base section 2 is provided in its upper side and adjacent its edges with grooves 6^a, 80 and on its upper side said base section is provided with parallel supports 7 which are curved upward in the direction of the length of the base section so that their intermediate portions are higher than their end portions. It will also be observed that the portion of the base section between the supports 7 is pitched downward from its middle to its opposite ends where it merges into the end grooves. It will also be noticed that below 90 the said pitched portion of the base section is provided a chamber 8 in the end walls of which are formed apertures 9 which are designed to connect the said chamber 8 with the interior of the upper section 1. 95

In addition to the upper section 1 and the base section 2, my novel vault comprises casket rests 10. These rests may be made of plastic material or any other material compatible with their purpose, and each 100 comprises sides 11 recessed at their ends as indicated by 12, and an intermediate portion 13 disposed between the sides at an intermediate point in the height thereof; all of the said recesses 12 being arranged at one 105 side of the intermediate portion 13, as illustrated, for an important purpose hereinafter described.

It will be manifest from the foregoing that when my novel vault is sealed, no water 110 can rise therein, and yet adequate drainage is provided for by reason of the pitched por-

tion of the base section 2 and the apertures 9. It will also be manifest that caskets can be supported at different heights in the vault by positioning the rests 10 at different distances apart on the supports 7 and also by inverting the rests.

Having described my invention, what I claim and desire to secure by Letters Patent, is:

- 10 1. In a burial vault, the combination with a base section having its under side shaped to form a chamber and also having its upper side inclined downward from an intermediate point in its length toward its ends and further having on its upper side longitudinal supports the upper sides of which are inclined downward from intermediate points in their length toward their ends; the lower portions of the said upper side and the said 20 chamber being connected through apertures formed in the base section, an upper section disposed on the base section, and casket rests arranged transversely within the upper section and adjustable on the longitudinal supports of the base section in the direction of the length of said supports.
- 25 2. In a burial vault, the combination of a base section having on its upper side longi-

tudinal supports the upper sides of which are inclined downward from intermediate 30 points in their length toward their ends, an upper section disposed on said lower section, and casket rests arranged transversely within the upper section on said supports and adjustable in the direction of the length of 35 the latter.

3. In a burial vault, the combination of a base section having on its upper side spaced longitudinal supports, an upper section disposed on said lower section, and casket rests 40 transversely arranged within the upper section and movably positioned on said supports; each of said rests having in its ends and at one of its sides recesses of a size to receive said longitudinal supports and enable 45 the portion of the rest intermediate the supports to occupy a position in a plane below the upper sides of the supports.

In testimony whereof I have hereunto set my hand in presence of two subscribing witnesses.

JAMES C. SNYDER.
